CARPET SWEEPER WINDOW

Carl C. Parrish, Shelbyville, Ind., assignor to
Porter Steel Specialties, a copartnership com-
posed of George M. Parker, Charles M. Youart,
and Hester Porter Fuller, Shelbyville, Ind.

Application April 1, 1939, Serial No. 265,379

2 Claims. (Cl. 189—77)

The object of my invention is to provide an efficient, low-cost, attractive structure by means of which the working of internal parts of a carpet sweeper may be readily observed.

5 The accompanying drawing illustrates my invention.

Fig. 1 is a perspective view of a sweeper embodying my invention;

10 Fig. 2 a plan of the sight opening through the top wall of the sweeper body;

Fig. 3 a plan of the finish ring to register with said opening;

Fig. 4 a section on line 4—4 of Fig. 1;

Fig. 5 a section on line 5—5 of Fig. 1; and

15 Figs. 6 and 7 fragmentary plans of modified forms of sight openings with the transparent plates indicated by dotted lines.

In the drawing 10 indicates the top plate or roof of the sweeper body 11 within which the 20 brushing mechanism is located.

Through plate 10 is formed a sight opening 12 of any desired size and general contour, except that the perimeter of the opening shall embody a plurality of inwardly projecting platforms 13 between each pair of which is a space 14 at the roots of the platforms. The transparent sheet 15 is so contoured as to lie upon the platforms 13 and to fall short of the edges defining spaces 14. The retaining ring 16 is provided, around 25 its inner periphery, with inwardly projecting spaced tabs 17 contoured to cover platforms 13, and between adjacent tabs 17 is a downturned tongue 18 having a width somewhat less than the extent of space 14 and a length sufficient to 30 permit its free end to be bent outwardly beneath plate 10, thereby holding the ring 16 and sheet 15 firmly in place.

It will be readily understood that the general shape and size of the sight opening and the 35 corresponding retaining ring may be widely varied without departing from my invention. The sight opening may be conveniently formed by a single punching operation and the transparent plate may be of any shape so long as it rests upon the 40 platforms and preferably does not protrude from

beneath the outer perimeter of the retaining ring, because the tongues 18 may perforate, or pass through perforations in, the transparent plate 15. I prefer, however, to so contour the transparent plate that, opposite spaces 14, the adjacent edge portions of the sheet will be spaced a tongue thickness from the adjacent portions of the perimeter of the sight opening so that perforation of the transparent plate will not be necessary but these portions of the edges of the plate will 10 fit closely against the downturned tongues 18 so as to present a neat appearance.

With this construction, the final finish may be readily applied to the roof plate 10 either before or after the sight opening is formed therethrough 15 and the transparent plate and the ornamental retaining ring may then be easily applied without damage to the finish of the upper surface of plate 10, and successfully hiding the platforms 13 which would be unsightly if left exposed.

20 I claim as my invention:

1. The combination with a hollow body with a wall having a perforation characterized by a plurality of laterally spaced inwardly projecting platforms, of a transparent plate resting on said platforms, and a retaining ring overlying the transparent plate and having at its inner periphery a plurality of tongues projected through the wall perforation between its platforms and bent outwardly to overlie the inner surface of said wall. 25

2. The combination with a hollow body with a wall having a perforation characterized by a plurality of laterally spaced inwardly projecting platforms, of a transparent plate resting on said platforms, a retaining ring overlying the transparent plate and having at its inner periphery a plurality of tongues projected through the wall perforation between its platforms and bent outwardly to overlie the inner surface of said wall and also having, around its inner periphery, a plurality of inwardly projecting tabs overlying and hiding the inwardly projecting platforms of the wall. 35 40
